UNITED STATES PATENT OFFICE

CARTER A. WILLIS, GORDON J. WILLIS, AND REUBEN M. WILLIS, OF CHANUTE, KANSAS,
ASSIGNORS TO THE WILLIS DRILLING MACHINE AND MANUFACTURING COMPANY,
OF CHANUTE, KANSAS, A CORPORATION OF KANSAS

DRILLING MACHINE

Application filed October 30, 1929. Serial No. 403,616.

Our invention relates to drilling machines and more particularly to that type of machine known as a spudding machine.

An object of the present invention is to provide a spudding machine wherein the drilling line or cable is permitted to reciprocate freely, this being due to the fact that the line does not have to be trained over a multiplicity of guide pulleys.

10 A further object of this invention is to provide a spudding machine whereby the drill cable will not be subjected to undue strain.

Still another object of the invention is to provide a machine of this character in which 15 the sand reel and drill cable drum are arranged to be driven from a common drive.

With the preceding and other objects and advantages in mind, the invention consists in the novel combination of elements, constructions and arrangements of parts and operations to be hereinafter more fully described, claimed and illustrated in the accompanying drawings, wherein:

Figure 1 is a front elevation of a drilling 25 machine construction in accordance with this invention;

Fig. 2 is a side elevation of the machine;

Fig. 3 is an enlarged fragmentary view 30 partly in elevation and partly in section; and

Fig. 4 is an enlarged fragmentary side elevation of the machine.

Referring to the invention in detail a conventional derrick 5 is provided and journaled in the lower end thereof is a drill cable drum 6 upon which the drill cable 7 is adapted 35 to be wound, the latter extending vertically and being trained over a pulley 8 carried by the upper end of the derrick.

A main power shaft 9 is arranged above 40 the drum 6 and is journalled in bearings 10 attached to the derrick. Supported below the power shaft 9 is a counter shaft 11 whose ends are received in eccentric bearings 12 so that the counter shaft may be moved toward 45 and away from the shaft 9. A friction drive gear 13 is fixed to one end of the shaft 9 while a small friction gear 14 is fixed to the counter shaft 11 so as to make contact with gear 13.

In order to move the counter shaft eccentrically to engage or disengage the friction

gear 14 to and from the friction gear 13 an arm 16 is fixed to one of the eccentric bearings 12. A hand lever 17 is mounted on one side of the derrick and is connected with the arm 16 by a link 18. It will be apparent that upon movement of the hand lever 17 in one direction the counter shaft will be raised to bring the friction gear 14 into contact with the friction gear 13 as disclosed in Fig. 3. To afford a driving connection between the counter shaft 11 and the drum 6 a gear 19 is keyed to the counter shaft and is adapted to engage a large gear 20 fixed to one end of the drum 6. The gear 19 is provided with a grooved collar 19a which is engaged by a yoke 21. A hand wheel 22 is revolubly mounted on the derrick to one side of the gear 19 and eccentrically connected thereto is a link 23 having one end operatively connected with the yoke 21. It will be apparent that upon rotation of the hand wheel in one direction the gear 19 will be slid into engagement with the gear 20 and that upon rotation of the hand wheel in the reverse direction this gear will be disengaged from the gear 20.

For the purpose of controlling the rotation of the drum 6 when the drill cable and tool are being lowered into the well a brake mechanism is provided comprising a brake drum 24 fixed to one end of the drum 6 and a brake band 25 encircling the same. One end of the brake band is anchored as at 26 while its opposite end is connected with a crank shaft 27 journalled on the base of the derrick. One end of the crank shaft is provided with a hand lever 28 which is operable to tension the brake band about the drum.

A horizontal sand reel 29 is journalled in the derrick above the shaft 9 and fixed to one end thereof is a friction drive gear 30 adapted to be brought into engagement with the friction gear 13 as disclosed in Fig. 3. The sand reel is mounted in the same manner as the shaft 11 and fixed to one end thereof is an arm 31. The arm 31 is operatively connected with a hand lever 32 supported adjacent the hand lever 17, by means of a relatively long link 33. Thus when it is desired to drive the sand reel, the lever 32 is actuated to shift the sand reel in a direction to engage the friction

drive 30 with the friction gear 13. The sand reel is prevented from overspeeding by a spring pressed shoe 34 which bears against the friction gear 30.

5 A cable 35 is adapted to be wound upon the sand reel and extends vertically of the derrick as disclosed in Fig. 2. The cable 35 is trained over a pulley 36 mounted in the upper end of the derrick below the pulley 8. A 10 conventional bailer 37 is suspended from the lower end of the cable. Normally the sand reel drive gear is elevated so that it will not be driven. However, when it is desired to raise the bailer from the well the sand reel 15 drive gear is lowered to the contact position disclosed in Fig. 2.

The invention provides a spudder for reciprocating the drill cable and drill tool. The spudder comprises a bell crank lever embodying 20 a pair of parallel spaced L-shaped bars 38. The bell crank lever is arranged between the opposite sides of the derrick and is movable about a horizontal shaft 39 supported by the derrick slightly above the sand reel. As 25 disclosed particularly in Fig. 4 the right angular part of the bars 38 are braced by brace rods 39a attached to these parts. The vertical leg of the bell crank lever carries a pair of guide pulleys 40 which are offset from each other to engage the opposite sides of the 30 cable 7. A relatively large pulley 41 is eccentrically mounted on a horizontal shaft 42 passing transversely through the horizontal branch of the bell crank lever.

35 An endless belt 43 is trained about the pulley 41 and extends downwardly and engages with a drive pulley 44 rotatable on but capable of being fixed to rotate with the power shaft 9, the power shaft having a driven pulley 45 which is engaged by an endless belt 46 driven from any suitable power source.

For the purpose of connecting the drive pulley 44 to the power shaft 9 a friction clutch 47 is mounted on the shaft and is 45 adapted to engage a clutch face 48 provided at one end of pulley 44. The clutch 47 is provided with a grooved collar 47a, the clutch and collar being slidably keyed to the shaft 9. A suitable hand lever 49 and suitable 50 linkage is provided for actuating the friction clutch 47 through grooved collar 47a.

In the operation of the spudder, rotation of the eccentrically mounted pulley 41 continuously rocks the bell crank lever about its 55 axis 39. In this connection it is pointed out that the endless belt 43 passing around the pulley 44 and eccentrically mounted pulley 41 constantly causes the axis 42 to shift and thus rock the bell crank on its axis 39. By reason of the rollers 40 engaging the cable 7 at opposite sides, the latter is alternately tensioned and released to reciprocate the drill tool attached thereto.

60 65 To facilitate moving the machine from one

well to another the derrick is mounted on a wheeled carriage 48.

What is claimed:

1. In a spudding machine, a derrick, a drill cable supported from the upper end thereof and extended downwardly, a drum supported at the lower end of the derrick upon which the cable is adapted to be wound, a rocker arm movable about a horizontal axis and operable to alternately lift and drop the cable, a rotatable element eccentrically mounted on said arm for continuously actuating the rocking member, and means for rotating said element. 70 75

2. In a spudding machine, a derrick, a drum journaled thereon, a cable to be wound about said drum and trained over the upper end of the derrick, a bell crank lever pivotally supported on the derrick for movement about a horizontal axis, means for rocking the bell crank lever including an eccentrically mounted driven pulley member carried by one arm thereof. 80 85

3. In a spudding machine, a derrick, a drum journaled thereon, a cable to be wound about said drum and trained over the upper end of the derrick, a bell crank lever pivotally supported on the derrick for movement about a horizontal axis, means for rocking the bell crank lever, and a roller carried by 90 95 the bell crank lever and operable to alternately raise the cable and permit the same to fall, such means including a rotatable member eccentrically mounted on the bell crank lever. 100

4. In combination, a drill derrick, a cable trained over the derrick, a bell crank lever supported on the derrick for movement about a horizontal axis, rollers carried by one leg of the bell crank lever and disposed upon opposite sides of the cable, a rotatable element eccentrically carried by the other leg of the bell crank lever, a driven pulley arranged along the rotatable element, and an endless belt engaged with the pulley and 105 110 rotatable element whereby to impart rocking motion to the bell crank lever.

5. A drilling machine including a derrick and a cable supported therefrom, a rocking member adapted to alternately lift and drop said cable, a pulley mounted on said rocking member, a drive pulley, one of said pulleys being eccentrically mounted, and a driving belt trained over said pulleys. 115

6. In combination a derrick, a cable trained 120 thereover, a bell crank lever pivoted intermediate the ends of one arm thereof for movement about a horizontal axis, cable engaging means carried by said arm, and means for rocking the bell crank lever including an 125 eccentrically mounted rotatable element carried by the other arm thereof.

7. In a spudder, a derrick, a drum supported thereby, a drill cable to be wound upon such drum and trained over the upper end of 130

the derrick, a bell crank lever pivotally supported on the derrick for movement about a horizontal axis, rollers carried by one leg of the bell crank lever and engaging the opposite faces of the cable, and means for rocking the bell crank lever whereby to alternately engage the rollers with the cable to rock the same, and subsequently permit the same to fall, such means including a rotatable member eccentrically mounted on the bell crank lever.
